ADDRESS CONTAINER

Alton L. Shirley, Cranston, R. I.

Application September 15, 1953, Serial No. 26,820

Term of patent 7 years

(Cl. D74—1)

To all whom it may concern:

Be it known that I, Alton L. Shirley, a citizen of the United States, residing at Cranston, State of Rhode Island, have invented a new, original, and ornamental Design for an Address Container, of which the following is a specification, reference being had to the accompanying drawing, forming a part hereof.

Fig. 1 is a perspective view of an address container embodying my new design. The back and sides present a hammered appearance in conformity with the hammered portions on the upper face, and

Fig. 2 is an end elevation thereof.

This application is a continuation in part of application Serial No. D. 25,211 filed May 27, 1953, for address container for ladies' handbags.

I claim:

The ornamental design for an address container, as shown and described.

ALTON L. SHIRLEY.
